UNITED STATES PATENT OFFICE.

ARTHUR J. CANFIELD, OF CHICAGO, ILLINOIS, AND ERNEST R. VIBERG, OF MONTREAL,
QUEBEC, CANADA.

METAL CAR ROOF.

Application filed December 1, 1921. Serial No. 519,202.

To all whom it may concern:

Be it known that we, ARTHUR J. CANFIELD, a citizen of the United States of America, and resident of the city of Chicago, in the 5 State of Illinois, and United States of America, and ERNEST R. VIBERG, a subject of the King of Great Britain, and resident of the city of Montreal, in the Province of Quebec, and Dominion of Canada, have 10 invented certain new and useful Improvements in Metal Car Roofs, of which the following is a full, clear and exact description.

This invention relates to improvements 15 in metal roofs, especially for freight cars, and the object of the invention is to provide a roof of simple, inexpensive and durable construction.

A further object is to provide a roof 20 which may be manufactured at a low cost and applied with great ease, and without the use of bolts.

A still further object is to provide a metal roof construction of comparatively light 25 weight, which eliminates the use of ridgepoles, carlines, subcarlines, purlines, and subpurlins without in any way weakening the car.

Another object is to provide a metal roof 30 which will yield to the movement of the car without opening any of the roof joints or otherwise causing leaking of the roof, and yet substantially brace the car.

Yet another object is to provide a roof of 35 simple construction which will be absolutely weatherproof and which will not form pockets for the lodgment of cinders and the like.

At the present time there is considerable 40 demand for metal car roofs on account of their fireproof and weather-proof qualities. These metal roofs must, however, comply with certain requirements and this compliance with requirements as to joints, thickness of plates, etc. considerably complicates 45 the manufacture thereof and renders it quite an expensive matter to provide the necessary dies. Furthermore, existing roofs are applied over a framing substantially the same as used for wooden roofs.

According to the present invention, a roof 50 is provided of such construction that the expense of manufacture and application is reduced to a minimum and furthermore, the necessity for roof framing is eliminated.

The invention consists essentially in pro-

viding a series of trough- or channel-shaped members extending transversely of a car at suitable intervals and serving both as carlines and as roof plates. The spaces between the channels are filled by plates having sliding and interlocking engagement with the channels. 60

In the accompanying drawings which illustrate one embodiment of the present invention:—

Fig. 1 is a fragmentary, perspective view 65 of the roof in position on a car.

Fig. 2 is a cross section on the line 2—2, Fig. 1.

Figure 3 is a fragmentary, longitudinal 70 section near the centre of the car.

Fig. 4 is an enlarged fragment of one end of Figure 2.

Fig. 5 is an enlarged fragment of Figure 3. 75

Fig. 6 is a fragmentary side elevation illustrating the junction of the roof members on the eave.

Referring more particularly to the drawings 11 designates the side and 12 the end of 80 a car which as illustrated, is a freight car. The roof comprises channel-shaped supporting member 13 and roof plates 14 alternated with the channel members and both extending transversely of the car. 85

The channel members 13 each comprise a bottom portion 15 slightly arched upwardly between the sides of the car and provided at each end with a downturned lip 16 to engage over an angle 17 attached to, or forming 90 a part of the car side, these angles forming supports for the ends of the channel members. Each channel member is formed with a pair of upstanding side flanges 18 which are deepest midway between the ends 95 of the member and taper to substantially no height at all at the ends of the member. The upper edges of these channel flanges are preferably grooved smoothly and continuously from end to end, as shown in Figure 100 2. Each flange is outwardly turned at its upper edge as at 19 and is then bent back on itself or inwardly turned at 20 to form two substantially parallel spaced portions. At the ends of the channel members where 105 the flanges 18 have diminished to no height at all, the portions 19 are continuous or substantially continuous with the bottom portions 15, as clearly shown in Figure 6. It will also be noted that the portions 19 and 110

20 stop short of the downturned lips 16, so as to leave the space 21 between them open at the ends of the channel. The channel members 13 are placed transversely of a car at 5 suitable intervals, the lips 16 holding them against movement transversely of the car. They may be riveted or bolted to the members 17 as desired.

The roof plates 14 are turned over at 10 their longitudinal edges to provide hook portions 22 spaced from the bodies of the plates and adapted to enter the spaces 21 in the channels, as shown best in Figures 5 and 6. These plates are of comparatively 15 thin metal and are preferably prepared in the flat, that is, without any curvature such as is evident in Figures 1 and 2. One end edge of each plate is turned downwardly as indicated at 23, the hook portions 22 being 20 necessarily pinched against the body of the plate where it is bent. The opposite end of each plate 14 is not thus bent down. To apply the plates 14 the hook portions 22 at the end of the plate are inserted in the openings 25 21 of adjacent channel members and the plates 14 slid transversely of the car until the downturned end portions 23 engage the lips 16 of the channel members. With a properly dimensioned plate it will be found 30 that at the opposite side of the car the end of the plate projects beyond the ends of the channel members. This projecting edge is bent downwardly, thus holding the plate 14 against removal. When all plates 14 are in 35 position it will be found that a continuous roof is provided jointly by the members 13 and 14. At the ends of the car the roof plates, designated 14^a, may be specially formed with a comparatively deep downturned flange 24 at one long edge, this flange 40 being adapted to overlie the car end. The downturned end portions 23 of the roof plates 14 may, if desired, be bent inwardly under the members 17, as shown at 25, Figure 4. This inward bending will serve to 45 hold the roof down on the body of the car independently of rivets securing the channel members.

The running board, designated 26, may be 50 supported at suitable intervals by means of brackets 27 riveted to the upstanding flanges 18 of the channels 13. As the smooth sheet metal roof will make very dangerous foot- 55 ing between the side and end ladders and the running board, any suitably formed tread surface 28 may be supported by brackets 29 and 30 attached respectively to the car and to the running board, or otherwise as may be desired.

60 A roof of the character just described is, it will be noted, composed of a comparatively small number of easily made and inexpensive parts which may be very easily and quickly applied to a car. The channel members 13, which form a part of the roof itself,

serve to support the remainder of the roof and therefore replace the carlines and pur-lins ordinarily used. The downturned ends of these channels, together with rivets, serve to hold the car sides from bulging and therefore to support the car body. The camber in the bottom portion 15 of these member is very slight and sufficient stiffness is imparted by the upstanding flanges to prevent the members straightening out under the 75 comparatively slight tension stresses to which they will be subject. The roof plates 14 which interlocked with the channel members, serve the double purpose independently of the rivets, of holding these members in proper position relatively to the ends of the car and also holding the entire roof down on the car body. The interlocking members 13 and 14 provide a roof which cannot materially elongate or materially shorten, but which has sufficient flexibility by reason of its slip joint seams to permit the roof to yield to movement in the car body without affecting in any way the weather-proof qualities or security of the seams. Obviously, 90 when the ends of the members 13 are riveted to the members 17 a very stiff and rigid roof will be provided, and as the members 13 are of considerable width they will become very effective diagonal braces. 95

The joints or seams between the members 13 and 14 are absolutely weather-proof. It will be readily seen that it is impossible for rain or grit to be driven through these joints by even the highest winds, as the direction of movement in getting through the seams must necessarily be reversed twice, i. e., once in passing round the edge of the hook portion 22 and the second time in passing round the edge of the portion 20. The hook portions 22 may be made a very easy fit in the recess 21 in order to facilitate application of the plates 14. Since, however, the upper edges of the channels 13 are curved and the plates 14 are straight before application, it will be apparent that the bending of the plates 14 which occurs when they follow the grooves 21 will cause the plates or their hook flanges 22 to bind very tightly against the channel members 13. This ensures a 115 tight surface joint throughout the length of every seam and also holds the plates 14 against rattling.

The channel members 13 have sufficient 120 camber to afford perfect drainage in the transverse valleys which they form in the finished roof, and the camber of the plates 14 when in place will be more than sufficient to ensure drainage. The channel members 13 will be preferably pressed or 125 rolled plates and the junction of their central webs 15 and flanges 18 will therefore be smoothly curved, as clearly shown in Figure 5 and without crevices for the lodgment of moisture or cinders. The distance between 130

flanges is such that wind will readily clear out any cinders which may lodge in the valleys.

The advantages of this invention are numerous. The framing forms a part of the roof, or the roof is supported without frame work, according as one considers the matter. No bolts are used in the construction and only a few rivets are necessary to connect the channel members. The roof sheets can be readily replaced without disturbing the channels and without the use of any tools beyond a bar and hammer. The number of pieces and the weight are quite small, and the roof is absolutely weather-tight. The channel members form a very strong top construction for a car and effectively brace the same against swaying. Such swaying motion as there may be has no detrimental effect on the roof construction or the tightness of the seams.

Having thus described my invention, what I claim is:

1. In a car roof, a transverse member comprising a central web, upstanding flanges at the edges of said web, said flanges decreasing in height from the centre towards the end of the web, and terminating a short distance from each end of the web, and lateral flanges on the upstanding flanges folded upon themselves to present grooves.

2. A device according to claim 1 in which the upstanding flanges diminish to no height at all adjacent the ends of the web, whereby said lateral flanges merge into the web adjacent the ends thereof.

3. In a car roof, a series of transverse members of sufficient length to extend from side to side of the car body, each of said members being provided with curved channels extending longitudinally thereof, a pair of outwardly extending eaves members ex-

tending along the upper side edges of the car body and supporting said transverse members, the ends of the transverse members being turned downwardly around the eaves members to provide depending ribs holding the transverse members against longitudinal displacement, and a series of normally flat roof plates inserted between said transverse members with the edges of the plates engaged in said channels and the ends of the plates turned downwardly and inwardly around the eaves members to hold both the transverse members and the roof plates thereto.

4. In a car roof construction, the combination of a series of transverse members of sufficient length to extend from side to side of the car body, eaves members extending along the upper side edges of the car body and supporting the transverse members, each of said transverse members comprising a web resting on the eaves members and having its extremities turned downwardly around the eaves members to prevent longitudinal movement of the web, a pair of flanges rising from the web and having the upper edge portions thereof reversely folded to provide a pair of longitudinally extending channels, a series of roof plates positioned between said transverse members and supported on said flanges with the side edges of the roof plates turned inwardly and disposed in the channels of the supporting transverse members, the ends of said roof plates being turned downwardly and inwardly around said eaves members to provide an anchorage for the plates and the transverse members.

In witness whereof, we have hereunto set our hands.

ARTHUR J. CANFIELD.
ERNEST R. VIBERG.
